(57) **CLAIM**

The ornamental design for a hairstyler, as shown and described.

DESCRIPTION

FIG. 1 is a front perspective view of the first embodiment of my new design for a hairstyler.

FIG. 2 is a left side elevation view of FIG. 1, the right side being a mirror image thereof.

FIG. 3 is a top plan view of FIG. 1.

FIG. 4 is bottom plan view of FIG. 1.

FIG. 5 is a back side elevation view of FIG. 1.

FIG. 6 is a front side elevation view of FIG. 1.

FIG. 7 is a front perspective view of the hairstyler of FIG. 1 with the hairstyler being closed, it being understood that all other surfaces are the same as those of FIG. 1.

FIG. 8 is a left side elevation view of FIG. 7, the right side being a mirror image thereof.

FIG. 9 is a top plan view of FIG. 7.

FIG. 10 is bottom plan view of FIG. 7.

FIG. 11 is a back side elevation view of FIG. 7.

FIG. 12 is a front side elevation view of FIG. 7.

FIG. 13 is a front perspective view of the second embodiment of my new design for a hairstyler.

FIG. 14 is a left side elevation view of FIG. 13, the right side being a mirror image thereof.

FIG. 15 is a top plan view of FIG. 13.

FIG. 16 is bottom plan view of FIG. 13.

FIG. 17 is a back side elevation view of FIG. 13.

FIG. 18 is a front side elevation view of FIG. 13.

FIG. 19 is a front perspective view of the hairstyler of FIG. 13 with the hairstyler being closed, it being understood that all other surfaces are the same as those of FIG. 13.

FIG. 20 is a left side elevation view of FIG. 19, the right side being a mirror image thereof.

FIG. 21 is a top plan view of FIG. 19.

FIG. 22 is bottom plan view of FIG. 19.

FIG. 23 is a back side elevation view of FIG. 19; and,

FIG. 24 is a front side elevation view of FIG. 19.

The features shown in broken lines illustrate portions of the hairstyler and form no part of the claimed design.
